[57] **ABSTRACT**

A gear pump, particularly for pumping gasoline under high pressures, comprises two intermeshed gears on substantially parallel shafts and an annular casing of substantially the same thickness as the gears surrounding the periphery of the gears and held between two casing covers arranged on respective sides of the gears which carry bores for receiving and rotatably supporting the shafts. The gears of the pump each include a bore having a raised or crowned central portion which bear on the gear mounting shaft and they are secured for rotation with the shaft by a bolt or connecting pin which extends diametrically through the shaft and engages at its projecting ends in cross-grooves defined in the gear bores. The gears are held against lateral displacement by lock washers secured to the shaft on each side of the gear.

GEAR PUMP

SUMMARY OF THE INVENTION

This invention relates, in general, to a construction of pumps and, in particular, to a new and useful gear pump particularly for pumping gasoline under high pressure conditions and having two externally toothed gear wheels mounted on two parallel shafts which are secured to the shaft by a pin which extends through the shaft and projects into a cross-groove of the associated gear.

The present gear pumps for gasoline delivery do not permit very high pressures and are susceptible to operating troubles so that they do not provide a long service life with high reliability. Particularly with pumps that are used for the delivery of gasoline, for example, in connection with the injection of gasoline into automotive engines without carburetors, a very high reliability and thus a long service of the pump are important.

In the known gear pumps of the above type the gear wheels are secured by means of adhesives on their shafts in order to ensure an accurate circular and transverse movement, since high pressures are required when delivering gasoline in connection with direct gasoline injection without a carburetor. This also requires a high precision in the manufacture of the casting and casing covers. But such a high precision in the machining of these parts can only be achieved for custom models, but not in mass production. In order to avoid this requirement for great precisions in the manufacture of the above mentioned parts, ways had to be found to build nevertheless gear pumps with maximum safety and high pressures.

This is achieved according to the invention by making the bores of the two gear wheels so that they are crowned or raised at the center to provide a ring-shaped contact between the gear wheel and the shaft in the center of the gear wheel width. This has the effect that no additional play is required between the lateral bearing surfaces even if the shafts are not absolutely perpendicular to the lateral bearing surfaces of the casting covers or when there is rubbing planar engagement of the gear end faces on the gear bore. The small wobbling movement of the gears on the shaft required for correcting any defects is made possible by the crowned bore in the gear and this is possible without causing any disadvantages. Preferably the torque between the gears and their shafts is transmitted by a cylindrical pin inserted transversely through the shaft and into two opposing parallel grooves defined in the gear bore.

This arrangement ensures the proper entrainment of the shafts to the gears and the gears are not statically overdefined with the lateral bearing surfaces. The gears adjust themselves automatically corresponding to the lateral bearing surfaces. The otherwise extremely high precision requirements in the manufacturing tolerances of the center distances between gears which are of the order of one/ten-thousandths inch can thus be so far reduced that mass-production becomes possible.

Accordingly, it is an object of the invention to provide a gear pump having a pair of interengaged pump gears which are mounted on spaced parallel shafts which are supported in casing covers on each side of the shaft and which abut against the sides of the gear wheels and an annular casing surrounding the gears of

2

substantially the same thickness as the gears, the casing being sealed between the covers and being manufactured to provide a close running peripheral tolerance to the operating gears, and wherein the gears have crowned shaft mounting bores and are secured to their associated shafts by a cross pin extending through the shaft and engage in a cross groove of the bore at each end.

A further object of the invention is to provide a pump of good capacity and durability which is simple in design, rugged in construction and economical to manufacture.

For an understanding of the principles of the invention, reference is made to the following description of a typical embodiment thereof as illustrated in the accompanying drawing.

BRIEF DESCRIPTION OF THE DRAWING

FIG. 1 is a perspective view partly in section of a gear pump constructed in accordance with the invention;

FIG. 2 is a partial axial sectional view showing the gear mounting, and

FIG. 3 is a section taken on the line III—III of FIG. 2.

DETAILED DESCRIPTION OF THE PREFERRED EMBODIMENT

Referring to the drawing, in particular, the invention embodied therein comprises a gear pump including an annular casing, generally designated 1, which surrounds two operable interengaged gear elements or gears 2 and 3.

In accordance with the invention the gears 2 and 3 are secured on spaced parallel shafts 4 and 5, respectively, by means of a through bolt or pin 20 which extends diametrically through the associated shaft 4 or 5 and is engaged with each end in a cross-groove 21 of the associated gear. The grooves 21, 21 are defined at diametrically opposite locations in a centrally crowned bore of the groove. The gear bores are rounded to a central high point or crown to define a central ring-shaped contact 25 between the gear and the shaft.

The gear wheels 2 and 3 are made of a nitriding steel and are nitrided at least on the surfaces, particularly on the teeth and the lateral surfaces. The shafts 4 and 5 are supported by means of needle bearings 6 and 7 and 8 and 9, respectively. The needle bearings 6, 7, 8 and 9 are supported in respective casing covers 10 and 11. The casing covers 10 and 11 are secured on each side of the casing 1 and abut against the respective sides of the casing 1 and the gear side surfaces. The gear pumping space is sealed by annular rings or gaskets 12 and 13, which are positioned in grooves defined in the respective covers 10 and 11. The gaskets 12 and 13, together with axial gaskets 14 and 15, provide a liquid seal for the pumping space. The shaft 4 is driven through a drive which includes a coupling 16. The whole assembly is secured together by screws or bolts 17 which extend through axial bores 18 and are tightened in an internally threaded bore end to pull the two casing covers 10 and 11 tightly against the respective faces of the casing 1 and up to the gears 2 and 3.

Liquid is drawn in through a suction opening 19 and discharged at the opposite side through a discharge opening (not shown) which connects to the gear chamber on a side opposite to the connection of the

inlet 19. When the drive shaft is turned in the direction of the arrow indicated on the coupling 16, the gasoline is drawn into the suction tube 19 and pumped out through the outlet which is not shown.

Axial locking between gear wheel 2 and shaft 4 is achieved by a locking washer 22 on each side of the gear wheels 2 and 3. These washers 22 are held in corresponding annular grooves in the associated shafts 4 and 5. Between the locking washers 22 and the gear wheel 2 there is some axial play so as not to hinder wobbling movements between shaft and gear wheel.

The two shafts 4 and 5 have the same diameter for supporting the shafts and for receiving the gear wheels 2 and 3, which means a simplification of the manufacture.

What is claimed is:

1. A gear pump particularly for pumping gasoline, comprising first and second parallel shafts, first and second gears mounted respectively on said first and second shafts for rotation therewith and being substantially of the same thickness and being interengaged for pumping operation, a casing of approximately the same thickness as said gears surrounding said gears, a casing cover secured on each side of said casing and bearing against said casing and rotatably supporting said parallel shafts, said gears having a bore with a raised central portion defining a ring-shaped contact between said gears and the associated shafts, said shafts including a torque transmission pin extending therethrough and having opposite ends engaged with said gear for connecting said gears for rotation with said shafts, and locking washers on said shafts on each side of said gears the gear thickness being less than the distance between its associated locking washers to allow a predetermined axial play therebetween.

2. A gear pump according to claim 1, wherein each of said shafts have the same diameter in respect to the portion thereof which supports said gear and the portions thereof which provide a rotatable bearing support.

3. A gear pump particularly for pumping gasoline, comprising first and second parallel shafts, first and second gears mounted respectively on said first and second shafts for rotation therewith and being substantially of the same thickness and being interengaged for pumping operation, a casing of approximately the same thickness as said gears surrounding said gears, a casing cover secured on each side of said casing and bearing against said casing and rotatably supporting said parallel shafts, said gears having a bore with a raised central portion defining a ring-shaped contact between said gears and the associated shafts, said shafts including a torque transmission pin extending therethrough and having opposite ends engaged with said gear for connecting said gears for rotation with said shafts, and locking washers on said shafts on each side of said gears the gear thickness being less than the distance between its associated locking washers to allow a predetermined axial play therebetween.

50

lel shafts, said gears having a bore with a raised central portion defining a ring-shaped contact between said gears and the associated shafts, a through pin extending through said first and second shafts, said first and second gears each including a cross-groove defined therein into which the respective ends of the associated pins of said first and second shafts are engaged, said first and second gears having a bore therethrough with a central crown forming a substantially central ring-shaped contact of said gears with the associated first and second shafts, a cross-groove defined through said bore at diametrically opposite locations, a through bolt extending through each of said shafts and engaged in the respective cross-grooves of said first and second gears, and a locking washer carried by said first and second shafts on each side of respective first and second gears for holding said gears in respect to axial movement in relation to the associated first and second shafts the gear thickness being less than the distance between its associated locking washers to allow a predetermined axial play therebetween.

4. A gear pump for pumping gasoline at high pressure comprising first and second parallel shafts, first and second nitrided hardened steel gears mounted respectively on said first and second parallel shafts being of substantially the same thickness and being interengaged for pumping operation, a casing of a light metal alloy material and of approximately the same thickness of said gears surrounding said gears and in rubbing contact with the periphery thereof, a casing cover secured on each side of said casing and bearing against said casing and rotatably supporting said parallel shafts, said casing being made of a metal material with running-in properties and at least a lateral surface of said casing covers being in rubbing contact with said gears and having a hard surface of anodically oxidized metal material, said first and second gears each including a bore having a crowned central portion in engagement with the associated shafts, a torque transmission pin extending through said first and second shafts and engaged with said first and second gears respectively, said first and second gears each including a cross-groove for facilitating entry of the associated torque pin from a side thereof, and locking washers carried on such shafts on each side of said gears for preventing withdrawal of the gears from engagement over said torque pin the gear thickness being less than the distance between its associated locking washers to allow a predetermined axial play therebetween.
